UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

PORTABLE ELECTRIC LAMP.

1,195,728.

Specification of Letters Patent. Patented Aug. 22, 1916.

Application filed April 1, 1916. Serial No. 88,259.

To all whom it may concern:

Be it known that I, ADOLPH C. RECKER, a citizen of the United States, residing at Oakville, in the county of Litchfield and State of Connecticut, have invented a new and useful Improvement in Portable Electric Lamps; and I do hereby declare the following, when taken in connection with the accompanying drawings and the characters of reference marked thereon, to be a full, clear, and exact description of the same, and which said drawings constitute part of this application, and represent, in—

Figure 1 a side view partly in section of a portable electric lamp constructed in accordance with my invention. Fig. 2 a side view with the parts separated.

This invention relates to an improvement in portable electric lamps such as are commonly called flash lights, and particularly to lamps of this character with round cases made from metal.

The object of this invention is to form the case in two parts and connect them by an insulating band in which means are mounted for closing the circuit through the lamp; and the invention consists in the construction hereinafter described and particularly recited in the claim.

In carrying out my invention I form the casing in two parts, an upper shell 2 and a lower shell 3. These shells are duplicates of each other and can be reversed end for end. They are provided at opposite ends with threads and the adjacent ends are adapted to be coupled together by a band 4 of insulating material. The lower end of the lower shell 3 is closed by a cap 5 in the

usual way, and secured to the upper end of the upper shell is the usual head 6 containing a lamp and reflector. Mounted in the band 4 is a spring slide 7 one end of which is normally in contact with one of the shells and adapted to be moved into contact with the other shell by means of a button 8 projecting through a slot 9 in the band. In connection with a casing of this character the usual batteries are employed, being inserted into one end or the other, one pole of the battery being in electrical contact with the lower shell, and the other pole of the battery in connection with the lamp. By moving the button 8, the slide 7 can be moved so that the ends of the slide overlap the adjacent ends of the upper and lower case so as to close an electrical circuit through them. This construction insures the lamp remaining open when so desired, and readily permits of the application of various forms of heads; and as the shells are each less than half the length of the lamp, they can be produced at lower cost than long shells, and by increasing the width of the band the lamps can be made longer or shorter, as desired.

I claim:—

A portable electric lamp comprising an upper shell and a lower shell having their opposite ends threaded, a band for connecting the adjacent ends of the shells, a slide carried by said band and normally in contact with one shell and adapted to be moved into contact with the other shell, a cap closing the lower end of the lower shell, and a lamp-carrier secured to the upper end of the upper shell.

ADOLPH C. RECKER.
